UNITED STATES PATENT OFFICE

PHILIP BOK, OF READING, OHIO, ASSIGNOR TO THE UNEXCELLED MANUFACTURING COMPANY, INC., OF NEW YORK, N. Y., A CORPORATION OF NEW YORK

FLARE DEVICE

Application filed September 23, 1927. Serial No. 221,533.

This invention relates to pyrotechnic apparatus and has for its object the provision of a simple and inexpensive mechanism for igniting signal devices such as flares, explosives or the like.

Another object is to provide a device of the class referred to which is readily applicable to co-action with parachute controlled flares and similar devices.

Another object is to provide a device of this kind which is certain and efficient in operation.

Another object is to provide a novel means for igniting a flare automatically upon opening of a parachute attached thereto.

These and other objects are attained by the means described herein and disclosed in the accompanying drawings, in which:

Fig. 1 is an elevational view of a parachute flare in operative position having a device of the invention embodied therein.

Fig. 2 is a cross sectional view of a carrying and releasing case in which devices such as shown in Fig. 1 may be carried on balloon baskets, aeroplanes and the like.

Fig. 3 is an enlarged cross sectional view on line 3—3 of Fig. 1 showing the parachute body and attaching cords in a folded position.

Fig. 4 is a view taken on line 4—4 of Fig. 3.

Fig. 5 is a fragmental cross sectional view of an igniting tape forming a detail of the invention.

Parachute flares and kindred devices have been heretofore provided for the purpose of permitting a balloonist or aeronaut to release a night signal of somewhat lasting character, but the simpler devices were not altogether satisfactory because of the danger of burning the parachute while releasing it or, in the event of using the flare to assist in landing, the parachute if unfurled by the aeronaut would sometimes keep too close to the balloon or aeroplane to provide the most efficient light. Devices adapted to be released from a casing by actuating a pull cord have also been used for releasing a flare or the like from the bottom of a plane or balloon but these devices have not been altogether satisfactory because of the complicated structure of the ignition

mechanism and of the relatively higher expenses of providing such mechanism.

In the present invention there is provided a simple inexpensive and efficient device which comprises generally a suitable flare shell 8 which may take the form of a fiber or cardboard cylinder, open at both ends and having the major portion thereof packed with a slow burning light emitting compound 9. Adjacent the top of the cylinder 8 is a mounting base comprising a disc or bung 10 which seals the cylinder and separates the compound from the ignition apparatus of the invention. The ignition apparatus comprises a bracket 11 suitably secured to the top face of the bung and having upright lugs 12 with aligned perforations therein for receiving a suitable pin 13 upon which is rotatably mounted a suitable roller sleeve 14 about which a relatively wide fabric tape 15 is wound. A tiny piece of adhesive tape secures tape 15 to the sleeve to preclude slippage of the tape on the sleeve. A pair of guides 16 and 17 are disposed centerward of tape reel structure and have their lower faces suitably rounded and polished to permit the tape 15 to readily slip beneath them. The tape 15 carries on its lowermost face and adjacent the inner end or that end which is roiled about the sleeve a suitable friction material 18 which, upon rapid unreeling of the tape beneath the guides 16 and 17 ignites a combustible substance 19 disposed on the top face of the bung 10 between guides 16 and 17 for lighting suitably incased fuses 20 which are secured along the top of the bung and extend through suitable perforations 21 in the wall thereof downwardly along the outside of the casing and beneath it where, at 22 they are in contact with the bottom exposed face of the compound 9. Suitable members 23 which may be of paper, adhesive tape or the like serve to retain the wrapped fuses in position for insuring ignition of the compound 9. The parachute 24 has attached to its usual parachute cords 25 a pair of attaching strings or cords 26 which are suitably secured to the disc or bung 10 at their lower ends. The tape 15 is somewhat shorter than the cords 26 so that when the device is

dropped, the parachute will open and due to the weight of the cylinder, compound and associated parts the device will be given a violent jerk, thereby unreeling the tape and drawing the friction material 18 over the ignition material 19 for igniting fuse 20. It will be readily apparent that the entire device will be below and entirely clear of an aeroplane or balloon before ignition of fuses 21 takes place. After the tape 15 has been unreeled and has performed its work of igniting the fuses, the cylinder 8 remains suspended from cords 26 which are entirely protected against the fire at the bottom of the flare cylinder 8. Devices of this kind are adapted to be released from a suitable carrying case such as is shown in Fig. 2, or they may be dropped or thrown out from a plane or balloon without danger of instantaneously igniting the flare with the attendant dangers of burning the parachute or igniting any part of the balloon or aeroplane.

A cross sectional view of a carrying and releasing case is shown in Fig. 2 where a cylindrical container 27 suitably secured to a plane has a releasable bottom member 28 held by a suitable catch 29 which is actuated by a pull cord 30 to drop the device.

It is to be noted that there is no danger of burning the cords 26 of the parachute until the compound 9 is completely burned and exhausted and that the parts of the ignition mechanism are light in weight and inexpensive of manufacture and comprise but a few simple pieces of sheet metal and a piece of flexible tape. While the invention as herein disclosed is shown as especially adaptable to the heretofore difficult and expensive problem of igniting parachute flares, it will be understood that its use is not confined entirely to that field, as the device may be readily modified for application to other devices.

What is claimed is:

1. In a device of the class described the combination with a reel structure, a tape wound on said reel, a supporting means for the reel, a pair of guide means on said supporting means and adapted to receive beneath them the body of the tape for retaining one face thereof in frictional contact with the surface of the supporting means, and frictional combustion means carried by the face of the supporting means and the said face of the tape.
2. In a parachute flare the combination with a flare body, of a mounting base on the top thereof, means for attaching a parachute to the base, a guide means, a flexible tape slidably mounted for frictional contact with the base, co-operating frictionally ignited means carried by the base and tape, said tape being secured at one end to a parachute, and a fuse extending adjacent the guide means and to a point on the flare remote from the ignition means, dropping of the flare serving to

open the parachute and to draw the tape over the base for setting off the ignition material and igniting the fuse.

3. In a device of the class described the combination of a roller member, a flexible member attached to said roller and wound about it, a supporting base for the roller member, means for retaining the flexible member in slidable friction contact with said base, an inflammable substance on the base and a friction substance disposed on a portion of the flexible member and adapted to frictionally engage the inflammable material upon unwinding of the flexible material from the roller.

4. In a device of the class described the combination with a reel structure, a tape wound on said reel, a supporting means for the reel, a guide means on said supporting means and adapted to slidably receive the body of the tape for retaining one face thereof in frictional contact with the surface of the supporting means, and frictional combustion material carried by the face of the supporting means and the said face of the tape.

In testimony whereof, I have hereunto subscribed my name this 19th day of September, 1927.

PHILIP BOK.
